By his Attorney Geo A. Byrne

Inventor

UNITED STATES PATENT OFFICE.

RICHARD MAXWELL EATON, OF NIAGARA FALLS, NEW YORK.

SWITCH FOR ELECTRIC FLASH LIGHTS.

Application filed September 23, 1926. Serial No. 137,264.

This invention relates to electric flashlights and more particularly to electrical circuit closing devices or switches therefor.

Flash-light switches sometimes include, as 5 an actuating member, a slide adapted to be reciprocated with respect to the dry battery container between an open circuit position and a closed circuit position affording a continuous illumination. Switches have 10 also been provided which are adapted to be depressed from a circuit open position to a circuit closed position whereby an intermittent illumination may be obtained at the will of the operator.

15 One object of the present invention is the provision of a circuit closing device for electric flashlights which may be positively retained in circuit open position to prevent accidental closing of the circuit and exhaustion 20 of the battery current when, say, the flash light is packed for transportation or carried in the pocket. Accordingly, a locking device is provided which requires, preferably, a depression of the switch and then 25 a movement of translation thereof, in order to move the circuit closer from circuit open position. More particularly, the circuit closer comprises a slide which must be depressed against the action of resilient devices, 30 such as a spring, to disengage the same from a stop and then pushed forwardly to an operative or circuit closing position.

Another object of the invention is the provision of a switch capable of being locked 35 in circuit open position and also capable of affording an intermittent as well as a sustained flash or illumination. According to this aspect of the invention, a slide is adapted 40 to be locked in circuit open position and upon unlocking, is movable to one position where an intermittent flash may be obtained and to another position where a sustained flash is afforded.

The invention also seeks to provide a 45 switch structure of simple design in the interest of manufacture and use. To this end a resilient device for the slide is provided whereby the intermittent closing of the circuit is effected, which resilient device also 50 effects the locking of the slide in circuit open position and in the other positions serves as one of the electrical contacts of the switch.

These and other objects of the invention 55 and the means for their attainment will be more apparent from the following detailed description taken in connection with the ac-

companying drawings illustrating a preferred embodiment of the invention, in which—

Fig. 1 is a view, in elevation, showing one 60 form of electric flashlight to which the invention is applied, the switch being illustrated in middle or intermittent circuit closing position.

Fig. 2 is a longitudinal vertical sectional 65 view of a circuit closing device according to the present invention.

Fig. 3 is a plan view showing the slide.

Fig. 4 is a plan view showing one of the 70 electrical contacts.

Fig. 5 is a plan view showing the resilient 75 device serving as the other contact.

The switch according to the present invention is shown in Figs. 1 and 2 as applied to an electric flash light having a tubular 75 battery container or handle 6, whereof the cap or end 7 is removable for the insertion of dry cells and a removable head 8 contains the lens 9 and a reflector, not shown.

At a convenient point on the housing or 80 container 6, a casing 10 is secured having an opening or slot 11 formed in the top surface through which an irregular or knurled thumb piece 12 on the slide 13 projects for manual actuation i. e. depression and reciprocation. The container is also formed with an opening 14 through which a tongue 27 85 on a conductor strip 15 is adapted to extend.

The container 6 serves as part of the electrical circuit and connects, say, with the negative pole of the battery, not shown. The positive pole of the battery, as will be understood, contacts with the electric lamp. Contact 15 also contacts with the lamp, not shown, by means of the inwardly extending 95 lip 16, the contact being insulated from the container or shell 6 by an insulating element 17 which breaks the continuous circuit between the battery and the lamp and permits the interposition of a circuit closing device 100 or switch.

As clearly shown in Figure 2, the casing 10, conductor strip 15 and insulating element 17 are all secured to the wall of the container in one operation by means of the 105 rivets or eyelets located at each end of the switch casing.

In the illustrated embodiment a switch is provided which is movable between three positions, to wit, a circuit open position, in which the switch or slide 13 is preferably 110 locked; a position in which the slide may be

depressed to provide an intermittent contact or one which is made wholly at the will of the operator; and a permanent contact position in which the contact is sustained automatically to provide a continuing or constant illumination.

The first of these positions is shown in full lines in Fig. 2. There the slide 13 is in its fully retracted position, the circuit is open, the spring 18 has forced the slide upwardly against the top wall 19 of the switch case 10 and a stop 20 on the slide is in engagement with the end 21 of the slot in the top wall 19 of the housing 10 which prevents all reciprocation. In addition, a bowed portion 22 of the spring lies within a depression or indentation 23 in the container 6 as a further means of preventing relative displacement, the spring being also formed with a bowed portion 24 which lies within the upwardly extending indentation forming the thumb piece 12 to prevent relative movement of the spring 18 and slide 13.

To effect an intermittent flash the slide 13 is moved to the intermediate position shown in Fig. 1. To free the slide for movement, it is depressed against the action of the spring 18 until the stop 20 lies below the end 21 on the switch case 10. The slide may then be pushed forwardly until the spring loop 22 engages the depression 25 in the container wall. As the spring loop 22 snaps into the depression 25 an audible signal is given that the slide is in intermediate position and its movement is retarded so as to conveniently permit its manual positioning there.

In the intermediate position the slide may be depressed at will to form a contact and close the circuit between the container and the contact member 15. The spring 18 is conveniently availed of to this purpose. To this end the spring 18 is formed as a flat strip 1 as shown in Fig. 5, bent as previously described and formed at its one end with a downwardly extending contact 26. Then, when the slide is pressed downwardly, the contact 26 is brought into engagement with the lip 27 on the contact member 15 to close the circuit so long as pressure is applied. So soon as the pressure is released the spring returns to its normal form and breaks the circuit.

The third position of the slide is indicated in dotted lines in Fig. 2. Here the contacts 26 and 27 are always in engagement to afford a continuous or permanent illumination. The spring end 26 is held down all the time due to the fact that the stop is beneath the top wall 19 of the switch case and the extreme end of the resilient lip 27 is always in contact therewith due to its upwardly deflected form.

It will thus be seen that a flash light is afforded wherein the sliding switch element

is movable between three positions, the first, a circuit open position, preferably locked, the second, an intermediate position in which the slide may be depressed to effect a closing of the circuit at the will of the operator, and the third, a position in which the circuit is constantly closed to afford a continuous or permanent illumination. To retain the slide in locked position and to yieldingly return it to open the circuit in intermediate position the same spring is used and this spring is utilized in the interest of simplicity of construction as one of the electrical contacts of the switch.

Various modifications may be made in the configuration and disposition of the various component elements going to make up the circuit closing device as a whole. Certain aspects of the invention are capable of independent use as well as in the combination and no limitation is intended by the foregoing description or illustrations except as indicated in the appended claims.

I claim:

1. A switch for electric flashlights comprising a slotted casing, a contact strip projecting within said casing, a slidable member having an outwardly pressed portion extending through the slot in said casing and forming a thumb piece and a flat spring associated with the slidable member and having one end portion for engaging said contact strip, said spring having a bowed portion extending within the thumb piece, said slidable member having an open circuit position, a manually operable circuit closing position for establishing flashing contact and an additional circuit closing position for establishing permanent contact.

2. A switch for electric flashlights comprising a slotted casing, a contact strip projecting within said casing, a slidable member having an outwardly pressed portion extending through the slot in said casing and forming a thumb piece and a flat spring associated with the slidable member and having one end portion for engaging said contact strip, said spring having a bowed portion extending within the thumb piece, said slidable member having an open circuit position, a manually operable circuit closing position for establishing flashing contact and an additional circuit closing position for establishing permanent contact, and means for locking the slidable member in the open circuit position until said thumb piece has been manually operated.

3. A switch for electric flashlights comprising the combination with the flashlight shell formed with depressions and an opening, a contact strip secured to the shell and projecting through the opening, a slotted casing, a slidable member having a thumb piece projecting through the slot, a flat tension and contact spring fitting into the slid-

able member and having a bowed portion on its upper side extending within the thumb piece, said spring also having its lower side provided with a downward depression to snap into the depressions in the flashlight shell, said slideable member having an open circuit position, a manually operable circuit closing position for establishing flashing contact and an additional circuit closing position for establishing permanent contact.

4. A switch for electric flashlights comprising, the combination with a flashlight shell formed with an opening, a contact strip projecting through the opening, insulating

means between the strip and shell, a slotted 15 casing, a slideable member having a thumb piece projecting through the slot, a flat tension and contact spring associated with the slideable member and having a bowed portion extending within the thumb piece and 20 fastening means located at ends of the casing for securing the contact strip, insulating means and switch casing to the flashlight shell.

In testimony whereof I have hereto 25 affixed my signature on this 16 day of September 1926.

RICHARD MAXWELL EATON.
